Attorney.

UNITED STATES PATENT OFFICE.

FRANK H. ROBINSON, OF CLEVELAND, OHIO.

BOX.

SPECIFICATION forming part of Letters Patent No. 687,337, dated November 26, 1901.

Application filed December 5, 1900. Serial No. 33,809. (No model.)

To all whom it may concern:

Be it known that I, FRANK H. ROBINSON, a citizen of the United States, and a resident of Cleveland, in the county of Cuyahoga and 5 State of Ohio, have invented certain new and useful Improvements in Boxes, of which the following is a full, clear, and exact description, reference being had to the accompanying drawings, forming part of this specification. 10

My invention relates to an improvement in what is termed a "collapsible" box made of cardboard or other suitable material, which can be readily "set up" to assume box form, 15 and is more especially designed for use in the millinery trade, as will be more fully hereinafter set forth and described.

In the drawings, Figure 1 is a perspective view of a box constructed in accordance with 20 my invention, being in shape a prism. Fig. 2 is a similar view of a box, showing the opposite side from that shown in Fig. 1. Fig. 3 is a perspective of the box partially collapsed, and Fig. 4 is a perspective of the box 25 completely collapsed—the condition in which it is shipped and stored.

Like letters of reference indicate identical parts in the various figures.

It will of course be readily understood that 30 the box may be formed from a single blank of cardboard or other suitable material cut and scored to fold into the shape shown and specified, or when desired it may be formed from a number of blanks properly cut and 35 scored and secured together.

A B are the sides, which are shown of rectangular shape. One of said sides—in the drawings it being side or flap A—is provided with laps a a, while both sides A and B are 40 provided with a lap b. The ends C C, which are triangular in shape, are either made integral with the bottom and one of the sides, (in the drawings shown as side B,) or if made of separate sheets of cardboard secured 45 to said side B and the bottom. To permit of the collapsing of the box or bag, the ends C C are provided with a score c, running from the juncture of the side B and the bottom through the center of the ends, thus practically forming what may be termed "bel- 50 lows folds," permitting the ends C C to collapse or fold inwardly, and thereby protect-

ing the angles or corners, which would be apt to become worn and broken should the ends fold outwardly.

55

In order to more completely close the box and to that extent make it more dirt-proof at the point where the ends will contact with the side A, I prefer to provide the ends C C with laps d d, arranged to fold in at right angles to the ends. These laps d d, together with lap b on the side B, fold inwardly and lie adjacent the inner face of side A and not only make the box more dirt-proof, but also tend to brace the sides and ends, and 65 thus strengthen the box. The laps d d are of course scored at points coincident with the score c c in the ends C in order that the ends may be collapsed.

The box is set up by lifting side B, thereby 70 erecting ends C C, then folding the laps b on side B and d d on ends C C inwardly and bringing side A up into position, permitting its laps a a and b to overlap the ends C C and side B, as shown in Fig. 2. To hold the 75 box in its erected or set-up condition, I provide the draw-string e. One end of it is secured to one of the ends C and, passing through opening f in the side or flap A into the box, comes out through opening f' and 80 then back into the box again through opening f" and out through opening f'", and is fastened to the opposite end C. The draw-string is of sufficient length to permit the collapsing of the box, and then when drawn 85 taut by grasping it between the holes f' and f" the surplus will be sufficient to pass over the top of the box and be secured to the opposite side B, either by tying it to the loop g or fastened in any other convenient manner. 90 It will be readily understood that the draw-string may be differently arranged from the manner shown in the drawings or described above, this method merely being shown for the purpose of exemplification.

95

By my improvement it will be seen that a box is produced adapted more especially for use by milliners, who require a box or bag of sufficient depth to permit the ready insertion of a hat, with its delicate trimmings, without 100 in any way crumpling it and at the same time one that will prevent the hat from "knocking" about by reason of the sloping sides. Furthermore, my improved box per-

mits of more speedy manipulation than is true with some of the constructions heretofore used, as it is simply necessary to lift side B and insert the hat and then bring up side 5 or flap A, drawing on the draw-string between holes f' and f'' and the box is closed, which, with its laps, is quite snug and completely protects its contents.

The end or middle portion of the draw-10 string e when the box is set up may pass through a loop or ring fastened to side B and its surplus end be used as a bail for carrying the box. However, I do not wish to limit myself to the exact method of arranging the 15 draw-string shown and described; but

What I do claim as my invention, and desire to secure by Letters Patent, is—

1. A box or bag made of one or more blanks of cardboard or other suitable material, and 20 having bottom, sides, and ends, one of said sides forming the lid and secured to the bottom, the other side being secured to the bottom and ends, the two sides converging at the 25 top, said ends bisected by a score-mark passing from the juncture of said ends with the side to permit of the collapsing of the box, substantially as shown and in the manner described.

2. A five-sided box made of one or more 30 blanks of cardboard or other suitable material, the ends made triangular in shape, the ends, one of the sides, and the bottom being secured together, the other or disengaged side or flap forming the lid and being secured to the bottom, and being provided with laps arranged to overlap the juncture with the opposite side and ends, said ends provided with a score passing through their center to permit the collapsing of the box, substantially 35 as shown and in the manner described.

3. A box made of one or more blanks of cardboard or other suitable material, having 40 bottom, sides, and ends, the ends being se-

cured to the bottom and one of the sides, said sides and ends provided with laps, the ends 45 being triangular in shape to permit the disengaged side or flap to contact at the top with the opposite side, and its laps to overlap the juncture with the opposite side, and the ends, said ends being scored to permit the box to 50 collapse, in combination with a draw-string passing from one of said ends through the disengaged side or flap to the opposite end, whereby the box may be held in its "set-up" 55 condition, substantially as shown and in the 55 manner described.

4. A prism-form collapsible box made of one or more blanks of suitable material, comprising bottom, sides, and ends, the ends being secured to one of the sides and the bottom 60 and scored to fold upon themselves when the box is collapsed, the sides and ends provided with laps, the laps on the ends and one of the sides arranged to lie adjacent the inner face of the disengaged side or flap, and 65 its laps adapted to overlap the juncture of said sides and the ends, in combination with means for retaining the sides and ends in their "set-up" condition, substantially as 70 shown and in the manner specified.

5. A prism-form box made of cardboard or other suitable material, comprising bottom, sides, and ends, the one side, bottom, and ends being secured together, and the other side forming the lid and being secured to the 75 bottom, the ends being scored to permit their being folded upon themselves, in combination with means for securing the loose side or flap in place and for holding the box in its "set-up" condition, substantially as shown 80 and in the manner specified.
